COMBINATION STORM WINDOW

Edward J. Bart, Queens Village, N. Y.

Application April 13, 1954, Serial No. 422,742

1 Claim. (Cl. 160—103)

This invention relates to storm windows.

It is an object of the present invention to provide a double storm sash and double window screen structure wherein the storm sashes may occupy any position within the limits of their tracks in the same manner as regular windows.

It is another object of the present invention to provide a storm sash and double window screen structure wherein the window screens may occupy any position within the limits of their tracks in the same manner as regular windows, permitting screening from both top and bottom in summer.

It is still another object of the present invention to provide a storm sash and double window screen structure which eliminates the necessity of having to remove storm sashes for summer storage and screens for winter storage.

It is still another object of the present invention to provide a storm sash and double window screen structure wherein the storm sash is provided in two sections, each movable vertically, and a double window screen which may be used in conjunction therewith, both storm sashes and window screens being mounted in one partially removable window frame which is adapted to fit over a conventional window frame from the outside thereof with a minimum of installation and time and labor.

Other objects of the present invention are to provide a double storm sash and double window screen structure bearing the above objects in mind which is of simple construction, inexpensive to manufacture, has a minimum number of parts, is easy to use and assemble and efficient in operation.

For other objects and a better understanding of the invention, reference may be had to the following detailed description taken in connection with the accompanying drawing, in which:

Figure 1 is a view in outside elevation of a window frame to which the invention has been applied;

Fig. 2 is a vertical sectional view taken along the line 2—2 of Fig. 1;

Fig. 3 is an enlarged view of a portion of Fig. 2;

Fig. 4 is a transverse sectional view taken along the line 4—4 of Fig. 1;

Fig. 5 is a fragmentary perspective view of one end of a removable track forming part of the invention;

Fig. 6 is a fragmentary perspective view of one end of the master frame receiving the track of Fig. 5 and adapted to be mounted on the outside of the conventional window frame and

Fig. 7 is a fragmentary perspective view of one of the storm sashes and showing the spring means for retaining the sashes in any desired position along the tracks.

Referring now more in detail to the drawing, wherein similar reference numerals identify corresponding parts throughout the several views, there is shown in Figs. 1 and 2 a conventional window frame 10 including the customary header 11, sill 12 and side jambs 13 which slidably mount the upper and lower window sashes 14 and 15 respectively.

In the practice of my invention, a pair of vertical master frame members 16 are secured to the outside of the window frame 10 at each side thereof. Each master frame member 16 includes a flat portion 17 (Fig. 4) 5 adapted to lie flush with the outer face of the frame 10 and integrally formed along its outer longitudinal edge with a sharp edge 18 adapted to be embedded into the frame, the flat portion 17 being suitably secured to the frame, for example by means of wood screws, not shown. 10 Each of the flat portions 17 is integrally formed with a bevelled portion 19 which extends outwardly from the frame 10 which is in turn integrally formed with a flange 20 spaced from and substantially parallel to the outer face of the frame 10. A guide channel member 21 is 15 integrally formed on the inner face of the flange 20 (Fig. 4) and extends inwardly therefrom between the sides of frame 10 where it is integrally formed with a flange 22 extending substantially parallel to the outer face of the frame 10 and abutting the inside of the latter. 20 The flange 22 along the edge thereof in abutment with the inside of frame 10 is integrally formed with a rib 23 and a second rib 24 intermediate the rib 23 and guide member 21. It will be noted that the edge of the flange 22 remote from rib 23 extends towards the center of the 25 window beyond the outer face of guide member 21, providing with the latter and the flange 20 a three-sided guide channel.

A removable track 25 (Fig. 5) fits snugly within each of the master frame members 16 and includes an elongated plate 26 adapted to lie flush with the outer face of the guide member 21, the outer face of each of the plates 26 being integrally formed with the laterally spaced, longitudinally extending tracks 27, 28, 29 and 30. It will be noted that the track 27 is formed flush with the inner longitudinal edge of plate 26 while the track 30 is spaced inwardly from the outer longitudinal edge of plate 26.

An upper storm sash 31 and a lower storm sash 32 are provided for sliding movement in a vertical direction between the tracks 25; as shown in Fig. 2, the lower storm sash 32 is of a greater height than the upper sash 31.

The upper sash 31 includes an upper horizontal portion 33 (Fig. 2) and a lower horizontal portion 34 connected at their ends by vertical portions 35 (Fig. 7), the portions 35 being of substantially H-shaped cross section.

As shown in Fig. 7, the vertical portions 35 of H-shaped cross section provide outer, vertically extending grooves 36 which cooperate with corresponding grooves provided on the horizontal portions 34 and 33 to fixedly mount the window glass 37, the H-shaped members 35 also providing inner grooves 38 which receive therewithin the laterally aligned tracks 29. The double edges of the members 35 adjacent the plate 26 are integrally formed with inwardly extending ribs 39 which embrace the tracks 29 on each side thereof, secondary ribs 40 being provided intermediate the ribs 39 and groove 36. The upper storm sash 31, thus constructed, is adapted to slide vertically to any position upon tracks 29, the sash being retained in any desired position by means of a curved leaf spring 41 secured at one end within a slot 42 in portion 35 (Fig. 7), the other end of spring 41 being provided with a slot 43 which straddles the rib 40. The leaf spring 41 is also provided with a central longitudinal slot 44 which straddles the opposite rib 40. Thus, the leaf spring 41 will be at all times in tensional engagement with one face of the track 29, whereby to retain the sash 31 in the desired vertical position until forced upwardly or downwardly.

The lower storm sash 32 is of a similar construction to the sash 31 and includes the upper and lower horizontal portions 44 and 45, respectively (Fig. 2) connected by vertical portions 46. As shown in Fig. 4, the vertical portions 46 are of H-shaped cross section and provide

inner grooves 47 which cooperate with corresponding grooves provided in the upper and lower horizontal portions 44 and 45, respectively, to fixedly mount the window glass 48, the H-shaped members 46 providing outer grooves 49 which receive therewithin the tracks 27. A leaf spring 50 identical with leaf spring 41 is similarly mounted intermediate the ribs 51, the double edges of the members 46 being provided with ribs 52 which embrace each side of the tracks 27.

As shown in Fig. 2, the outer face of the horizontal portion 44 of lower storm sash 32 is integrally formed along its upper edge with a ridge 53 which fits within a corresponding groove provided on the inner face of the horizontal portion 34 of upper sash 31 along its upper edge and which cooperates with weather stripping 54 and 55 provided on the adjacent faces of the horizontal portions 34 and 44 respectively whereby to substantially seal off the entrance of wind. This arrangement is more clearly shown in Fig. 3 wherein the upper and lower sashes 25 and 32 are mounted on the tracks 29 and 28 respectively.

As shown in Fig. 5, the plate 26 is provided with inwardly stamped stops 57 which limit the extreme positions of the sashes.

Thus, the storm sashes 25 and 32 (arranged either as shown in Fig. 2 or in Fig. 3) may occupy the closed positions shown or any position intermediate the ends of the tracks 25.

As shown in Fig. 2, upper and lower window screen sashes 58 and 59, respectively, are provided for vertical movement intermediate the tracks 25. The lower window screen sash 59 includes the upper and lower horizontal portions 59' and 60 connected by the vertical portions 61 similar in cross section to the vertical portions 35 and 46 of sashes 25 and 32 respectively. The H-shaped members 61 provide outer grooves 62 which cooperate with corresponding grooves provided in the horizontal members 59' and 60 to fixedly mount the frame 63 of a wire screen 64. The double edges of the members 61 are provided with the ribs 65 which embrace the tracks 29 on each side, ribs 66 being provided intermediate the ribs 65 and grooves 62. Leaf spring 67 identical to leaf springs 41 and 50 straddle the ribs 66 whereby to retain the screen sash 58 at any desired vertical position.

The upper window screen sash 58 is identical in construction with the lower window screen sash 59 and includes the horizontal portions 68 and 69 (Fig. 2) connected at their ends by the vertical portions 70 identical in cross section with the vertical portions 61. The H-shaped portions 70 provide inner grooves which receive therewithin the track 30, the portions 70 also providing the outer grooves which cooperate with corresponding grooves provided in the horizontal portions 68 and 69 to fixedly mount the frame 71 of the wire screen 72. A leaf spring 73 (Fig. 2) identical to the leaf spring 67 retains the upper window screen sash 58 at any desired position.

When the window screen sashes 58 and 59 are arranged on tracks 30 and 29 (Fig. 2) the adjacent faces of the horizontal portions 59' and 69 will be provided with weather stripping similar to that described in connection with the storm sashes 25 and 32. Such weather stripping may, however, be eliminated when the window screen sashes are arranged on tracks 30 and 27, as shown in Fig. 3.

As shown in Fig. 2, the window screen sashes 58 and 59 may be removed upwardly past heading 11, if desired.

As shown in Fig. 2, the tracks 25 consist of upper and lower portions, the upper portions being fixed while the lower portions are removable.

It should now be apparent that there has been pro-

vided a storm sash and window screen structure including double storm sashes and double window screen sashes which may occupy all positions within the limits of their vertical tracks, the invention eliminating the necessity of having to remove storm sashes for summer storage and screen sashes for winter storage. It should also be apparent that there has been provided a storm sash and window screen structure including double storm sashes and double window screen sashes which are mounted in a single frame which may be permanently mounted upon the outside of the conventional window frame without marring in any manner the appearance of the building.

While various changes may be made in the detail construction, it shall be understood that such changes shall be within the spirit and scope of the present invention as defined by the appended claim.

I claim:

A storm sash and window screen construction comprising a pair of vertical frame members adapted to be mounted on the outside of a window frame, a guide channel on the inner face of each of said members, a removable track within each of said guide channels, a double storm sash adapted for vertical movement on said tracks, and a double window screen sash adapted for vertical movement of said tracks, each of said frame members including a flat portion adapted to lie flush with the outer face of the window frame, an outwardly extending portion connected to said flat portion, a flange on the end of said outwardly extending portion extending substantially parallel to the outer face of the window frame, a guide member on the inner face of said flange extending inwardly therefrom at substantially right angles to said flat portion and a second flange substantially parallel to the outer face of the window frame along the edge of said guide member remote from said first flange, said second flange abutting the inside of the window frame at one end and extending beyond said guide member at the other end whereby to provide a three-sided guide channel adapted to receive therewithin said tracks, each of said removable tracks comprising a plate adapted to fit within said guide channel and four longitudinally extending, laterally spaced rails provided on the inner face of said plate, the innermost of said rails being provided along the inner edge of said plate and adapted to lie flush with said second flange, the outermost of said rails being spaced from the outer longitudinal edge of said plate, each of said storm and window screen sashes along their vertical edges being provided with a groove adapted to receive a corresponding pair of laterally aligned rails therewithin in freely spaced relationship thereto, the outer double edges of each of said side edges of said sashes being provided with inwardly extending ridges adapted to engage said rails on opposite faces thereof, the side edges of each of said storm and window screen sashes on each side of said grooves being provided with a second pair of inwardly extending ridges, and friction means comprising a curved leaf spring within said grooves secured at one end to said side edges, the other end of said leaf spring having a slot straddling one of said second ridges, said leaf spring having a central longitudinal slot straddling the other, oppositely disposed ridge within each of said grooves.
